UNITED STATES PATENT OFFICE

2,269,745

SPRINKLER SYSTEM

Charles F. Troop, Valencia, Pa.

Application March 31, 1939, Serial No. 265,233

2 Claims. (Cl. 177—382)

My invention relates to new and useful improvements in sprinkler systems and fire extinguishment and more particularly to alarm means for use in such a system to indicate that the system is in operation so as to warn individuals that there is a fire.

An object of my invention is to provide an alarm unit having an alarm means and operating mechanism for controlling the same.

Another object is to provide a unit having an alarm means and which may be inserted in the pipe line of the sprinkler system.

The invention consists in the novel cooperative relation and arrangement of parts, to be more fully described hereinafter and the novelty of which will be particularly pointed out and distinctly claimed.

In the accompanying drawing, to be taken as a part of this specification, I have fully and clearly illustrated a preferred embodiment of my invention, in which drawing—

The figure is a view of a portion of a sprinkler system showing the alarm unit, but with certain casing cover members removed and certain parts in section for clarity of illustration.

Referring to the drawing by characters of reference, 1 designates generally a sprinkler system pipe line for water flow to the usual water discharge sprinkler head 2 closed by a fusible element 3 such that upon the occurrence of fire sufficient to raise the temperature of and fuse the element 3, the normally closed sprinkler head 2 will be opened to discharge water and put out the fire. Positioned in the pipe line 1 on the inlet side of the sprinkler head 2, there is a water pipe 4 through which all of the water flows to the sprinkler head 2 and which extends through apertures in the end walls 5, 6 of a substantially rectangular metal casing 7. The pipe 4 has within the casing 7 a Venturi tube portion 8 of converging-diverging bore providing a throat 9 for creating a reduced pressure on flow of water through the pipe 4. Positioned within the casing 7 there is a differential pressure operated switch 10 such as is shown in the patent to Dillman, 2,088,556, July 27, 1937, having a substantially rectangular housing 11 which carries opposed pressure responsive power elements 12, 13, preferably of the bellows element type, and which act in opposition to each other against the ends of an interposed thrust member 14. The pressure responsive chamber of the power element 12 is communicatively connected by a fluid pressure transmitting pipe or conduit 15 to the interior of the pipe 4 at the throat 9, as at 16. 55

The pressure responsive chamber of the power element 13 is communicatively connected by a fluid pressure transmitting pipe or conduit 17 to the pipe 4 adjacent to and on the inlet side of the portion 8. The pipe 17 also serves as a supporting means for the switch 10. The thrust member 14 which interconnects the power elements acts through a lever 18 pivoted at 18^a to hold the switch arm 19 pivoted at 19^a normally in open position against the force of the switch closing spring 20. The free end of lever 18 which is pivoted at 20^a to the thrust member 14, bears on a cross pin 20^b carried by the lever 19 in order to hold the switch in open position as shown until a desired pressure differential exists as will be described. The switch arm 19 carries a contact member 21 which is cooperable with a contact member 22 to close a circuit between lead wires 23, 24 connected to terminal posts 20 within the switch housing 11. Also positioned within the casing 7 and secured to the rear casing wall, there is a bell ringing transformer 25 having its primary terminals 26, 27 connected by lead wires 28, 29 respectively to a contact plug 25 30 secured in an opening through the casing end wall 5. Secured externally to the casing 7 and to the outside face of the rear casing wall, there is an electrically energized alarm means 31 having a bell 32 with a clapper 33 actuated by the usual electromagnet armature. The terminals 34, 35 of the alarm means are connected respectively to the switch lead wire 24 and by a lead wire 36 to one terminal 37 of the transformer secondary, the other transformer secondary terminal 38 30 being connected to the switch lead wire 23. The lead wires 24 and 36 extend through an aperture 39 in the rear wall of a casing 7. Also within the casing 7 there is a closed stand pipe 40 connected into the pipe 4 on the inlet side of the pressure transmitting pipe 17 and serving as an air cushion to reduce the effects of water hammer and water surges on the switch 10. The operation of my alarm unit is as follows: With the line 1 closed against discharge, the water pressure in the pipe 4 will act through the pipes 15 and 17 and be equal on the power elements 12 and 13 so that the thrust member 14 will be positioned as shown with the switch in open position. Any changes of head pressure in the system will be transmitted equally to the power elements 12 and 13 and therefore will not effect operation of the switch. However, should the sprinkler head 2 be opened to discharge water, then flow will occur in the pipe 4, resulting in a reduced pressure at the throat 9 with a

resultant reduced pressure of the power element 12 against thrust member 14. As soon as this reduction of pressure occurs, there will be an unbalance between power element 13 and power element 12 so that the greater pressure exerted in and by power element 13 will move the thrust member 14 upward or toward power element 12 and tending to move the free end of lever 18 away from cross pin 20^b, thereby permitting spring 20 to rotate switch arm 19 and close contact members 21 and 22. Closure of switch 10 at contact members 21 and 22 will complete the transformer secondary circuit, thereby energizing the alarm means 31 to cause sounding of the alarm bell. It should be noted that the rear wall of the casing 7 serves as a sound board for the alarm means 31 as well as serving to support the alarm means and the transformer.

What I claim and desire to secure by Letters Patent of the United States is:

1. A unitary alarm device comprising a sheet metal supporting casing, an electric alarm bell mounted exteriorly on a wall of said casing, a pipe extending through said casing thereby to support said casing, a casing within said first casing, switch means in said second casing and supported by said pipe, and means operable to move said switch means to closed position upon

flow of liquid through said pipe, said switch means controlling the circuit of said bell.

2. A unitary alarm device comprising a sheet material supporting casing having opposite wall apertures, a pipe extending through said apertures thereby to support said casing, said pipe having a portion within said casing of converging-diverging bore providing a throat, a casing within said first casing, a differential pressure operated switch within said second casing and having opposed pressure responsive elements positioned in said first casing, a conduit supporting said switch casing and connecting one of said elements to said pipe adjacent said portion, a conduit connecting the other of said elements to said throat so that upon flow through said pipe said switch will be closed, an electrically energized alarm bell having its circuit controlled by said switch, said bell being carried by an external wall of said first casing such that said first casing wall serves as a sounding board for said bell, a transformer in said first casing and having its secondary electrically connected to said switch and said bell, and a circuit terminal member carried by a wall of said first casing and electrically connected to the primary of said transformer.

CHARLES F. TROOP.
